UNITED STATES PATENT OFFICE.

WILLIAM P. WIEMANN, OF WASHINGTON, PENNSYLVANIA.

TACHOMETER.

SPECIFICATION forming part of Letters Patent No. 728,529, dated May 19, 1903.

Application filed January 28, 1902. Serial No. 91,605. (No models.)

To all whom it may concern:

Be it known that I, WILLIAM P. WIEMANN, of Washington, in the county of Washington and State of Pennsylvania, have invented a new and useful Tachometer, of which the following is a full, clear, and exact description, reference being had to the accompanying drawings, forming part of this specification, in which—

10 Figure 1 is a top plan view of my improved device, partly broken away. Fig. 2 is a central vertical section of the same, and Fig. 3 is a horizontal section on the line IIIIII of Fig. 2.

15 My invention relates to that class of tachometers wherein a rotary fan is actuated by the rotation of the shaft, the air-current caused by this fan acting upon a vane-indicator, which is thus moved to different points on the dial under the varying pressure caused 20 by the different speeds; and the invention is designed to simplify and improve such devices and make them portable, convenient, and practical.

25 In the drawings, 2 represents a metallic case, having a base 3 and a removable top crystal 4 with a dial or scale marked around its edge. The graduations of the dial are spaced successively a greater distance apart, starting at the zero-point, and I have found 30 by experiment that this is necessary in order to obtain accurate results on account of the successively-easier movements of the needle and reduced resistance of the spring. The driving-spindle 5 extends across the case from 35 side to side in a horizontal direction, is provided with a clutch-socket 5' at each end, and carries a miter-gear 6, intermeshing with a similar miter-gear 7, mounted on a stub-shaft 8, projecting vertically within the bottom of 40 the case. A spur gear-wheel 9 is secured to or formed integrally with the miter-gear 7 and intermeshes with a pinion 10, secured to a counter-shaft 11, to the upper end of which is secured a spur-gear 12. The spur gear-wheel 12 intermeshes with a centrally-located pinion 13, having secured thereto a disk 14, carrying fan-blades 15. The pinion 13, which carries the fan-wheel, rotates around the stem and below the head of a flat-head screw 15, in 45 which is centrally secured a stationary vertical pin 17. A needle 18, which is in the form of a vane with depending end portions

18' beyond and spanning the fan-blades, is soldered or secured to a sleeve 19. A short screw 20 is screwed into the upper end of the 55 sleeve 19, the lower tapered end of this screw being polished and resting upon the upper polished flat end of pin 17. The screw 20 projects above the sleeve, which is provided with a flange supporting an inertia-disk 21. 60 The disk has a central hole which the screw enters, allowing it to rest upon the flange, upon which it is free to rotate, giving a braking action.

To form a yielding resistance for the pointer-vane, against which resistance the air-currents act, I provide the spiral spring 22, having a hub 23, which is forced down over the stationary pin 17. The outer or free end of the spring is held by a sealing-wax clamp 24 70 at the lower end of the stem 25, secured to the pointer-vane. The vane or pointer is brought to zero by turning the spring-hub around on its carrying-pin, the strength of the spring being changed by unsealing and 75 moving the spring to a new position and resealing.

The gearing is arranged so that the driving-spindle 5 is parallel to the dial, and this gearing also provides for giving a high rotative 80 speed to the fan, both of these features being important to a practical and portable device. The disk 14 of the fan is provided with vent or circulating holes 26 near the center to allow air to be drawn from below to the point 85 from which the air is taken by the fan. The use of two connections at opposite ends of the shaft 5 enables the device to be applied to shafts turning in clockwise or counter-clockwise direction without changing the direction of movement of the vane. I thus prevent a reverse tension of the spring which would cause the spring to lose its adjustment.

In the operation of the device a center stem 5' is connected directly to the center of shaft 95 to be tested, and the fan is thus driven at a high speed. The air which is drawn through the holes in the fan-disk to the vane side is driven in a rotary current and becomes compacted at the outer edge of the wheel, thereby 100 actuating the vane, and more or less air is forced back to the other side of the disk through the space between the fan-wheel and the case. The vane which has been held in

proper normal position by the spring is thus deflected by the air-current from its normal position to some position at an angle thereto dependent upon the speed of rotation of the 5 fan. The inertia-brake 21 is not affected by the air-currents, but acts as a resistance to the start or stop of the vane upon which this disk rests and prevents an unsteady or hunting action of the indicator-vane, which would 10 come to a point of unsteady balance between the force of the spring and that of the air-currents. This unsteadiness is prevented by the action of the inertia-disk, which is light in weight but of large diameter. The disk is 15 not acted on by air or the spring-ring, but moves freely with vane in either direction. Its sole function is to retard sudden starts or stops of the vane. When both vane and disk are in motion, a sudden stop of the vane is 20 prevented by the disk. The friction between the disk and the flange on which it rests tends to prevent motion between both.

If force is applied to the vane sufficient to cause a quick movement thereof, the disk 25 will not move until the vane has started, the disk gaining speed as the vane advances, thus retarding the progress of the vane, and later the disk aids the vane and prevents a sudden start back when released by the force which 30 causes the swing. If the vane should tend to stop suddenly, the disk continues and the friction between the disk and the vane prevents a sudden stop and a backward swing, which would occur without the use of the 35 brake-disk. The momentum which is set up in the disk by movement of the vane as a result of the friction between the two retards the start of the vane, and if the power applied to the vane is insufficient to set up the 40 momentum in the disk no movement of the vane will result. Thus the unsteadiness of vane caused by balancing between the force of the air-currents and spring are prevented by the disk.

45 The advantages of the invention result from the use of the speeding-up gearing, which raises the rotating speed of the fan above that of shaft being tested to such a point that a practical instrument is thus obtained. Without this the speed of the fan-wheel would not be sufficient for a device of ordinary size. The action of the balance-disk is of peculiar advantage, as also the bevel-gear arrangement and the general com-

pact arrangement of the parts. The changing spacing of the graduations gives correct readings. The supporting of the needle-vane at the top gives a very sensitive adjustment and a much better action than where it is fixed to a shaft having two bearings, and the 60 means for attaching to either end of the shaft 5 makes the device economical.

Many variations may be made in the form and arrangements of the parts without departing from my invention.

I claim—

1. A speed-indicator or tachometer having a rotary fan-wheel with inlet-openings therethrough, mechanism for rotating the fan-wheel, and a pointer-vane spanning the wheel 70 and actuated by the currents therefrom; substantially as described.

2. In a speed-gage or tachometer, a fan-wheel provided with a disk having circulating air-inlets therethrough, and mechanism 75 for rotating the same; substantially as described.

3. A tachometer having a rotary fan-wheel, a vane or needle acted upon by the air-currents, and an inertia-brake disk for the vane 80 or needle having its weight equally distributed around the axis of the needle; substantially as described.

4. A tachometer having a fan-wheel, an indicator-vane having an annular flange, and 85 an inertia-brake disk surrounding the vane-shaft loosely and supported on the flange, to exert a braking friction on said flange; substantially as described.

5. A tachometer having a fan-wheel, a stationary pin projecting upwardly above the fan-wheel and an indicator-vane above and 90 spanning the blades of the fan-wheel and supported at the top on the pin; substantially as described.

6. In a tachometer, a vane supported on a stationary pivot and having an adjustable clamp connection with the outer end of a spiral spring, and a rotatory fan-wheel arranged to act upon the vane; substantially 100 as described.

In testimony whereof I have hereunto set my hand.

WILLIAM P. WIEMANN.
